DESIGN FOR A VENTILATOR CASING

Fowler Manning, Bronxville, N. Y., assignor to
American Radiator Company, New York, N. Y.,
a corporation of New Jersey

Application September 21, 1935, Serial No. 58,643

Term of patent 14 years

To all whom it may concern:

Be it known that I, Fowler Manning, a citizen of the United States, residing at Bronxville, in the county of Westchester and State of New York, have invented a new, original, and ornamental Design for a Ventilator Casing, of which the following is a specification, reference being had to the accompanying drawing, forming part hereof.

In said drawing—

Figure 1 is a view in perspective of a ventilator casing embodying my new design, and

Figure 2 is a top plan view thereof.

I claim:

The ornamental design for a ventilator casing, as shown.

In witness whereof, I have hereunto subscribed my name.

FOWLER MANNING.
